CLAIM

The ornamental design for the control elements with surface ornamentation, as shown and described.

DESCRIPTION

The sole FIGURE of the drawing is a plan view of the control elements with surface ornamentation showing our new design.

The sides and the back of the design do not form a part of the claimed design.

The outline of the key panel according to the invention is shown in broken lines, indicating that the device may take any form, footprint shape, or size, and does not form a part of the claimed design.

The broken lines define the bounds of the claimed design.
